UNITED STATES PATENT OFFICE

SIDNEY SPRAGUE, OF NEW YORK, N. Y.

COMBINED CIGARETTE CASE AND LIGHTER

Application filed March 22, 1928. Serial No. 263,819.

This invention relates to improvements in a cigarette case and lighter, presenting a novelty as a two in one article, and contributing in a considerable degree to the facilities and incidental comfort so highly valued by smokers.

As this invention notwithstanding the new and genuine features embodied therein is very simple of construction, the manufacturing 10 cost of same should be comparatively low.

The object of the device is briefly to provide a cigarette case and a lighter adapted to cooperate in such a manner, that through an insignificant operation a cigarette will be ejected and simultaneously lighted.

It is thought desirable here to point out, that the invention embodied and described in this application constitutes further improvements of a somewhat similar device for which 20 the United States patent application has been filed by me January 20, 1928, under Serial No. 248,112.

With the above and other objects in view, this invention consists of the novel features 25 of construction, combination and arrangements of parts, hereinafter fully described, claimed and illustrated in the accompanying drawings forming parts of this specification, and in which similar characters of reference 30 indicate corresponding parts in all views, and in which:

Figure 1 illustrates my cigarette case and lighter as an ensemble in closed position; Fig. 35 2 shows my device in an ordinary open position in course of ejecting a cigarette; Fig. 3 is a perspective view of one sector of my device; Fig. 4 represents a transverse sectional view taken on line 4—4 of Fig. 1; Fig. 5 is a perspective view of my device with the lid of 40 the case swung open; Fig. 6 is a sectional side elevation of my device, especially illustrating the lighting mechanism while Figs. 7 and 8 represent detail views for further illustrative purposes.

45 Referring more particularly to the drawings, 10 indicates the embodiment of my device, comprising a front member 11 formed with a flat bottom 12 and somewhat curved sides 13 and 13¹, adapted to be snapped onto 50 and slidably engage a counter, or rear mem-

ber 14 with its hingedly attached box-compartment 15, respectively. The said front member 11 has further arranged a partition 16 as an additional support for the said box-compartment 15; an opening 17 of a somewhat rectangular shape formed at one side of the latter is adapted to register with an opening 18 of a substantially corresponding shape formed in the said partition 16 for the purpose of conveying light to a cigarette, 55 when the said device-ensemble is subjected to its two stroke manipulation.

The front member 11 is still further provided with a top flange 19 extending between one side and the partition 16; the said flange 60 has in close proximity to the latter arranged a circular reduced portion 20 to permit the ejection of a cigarette. The said front member 11 is arranged with an inner semi-wall 21, which by a bending or stamping process 65 may be made to form an integral part with the said front member, the flat bottom 12 and the side portion 13, and which is rigidly connected to the partition 16, being near the latter provided with a cut-out portion 22 in order to permit the projecting arm 23 of the counter part 14 to engage and eject a cigarette 70 24, as the latter by means of a pair of spring members is placed in suitable position therefor.

75 The said spring mechanism, comprises substantially two flat, resilient steel members 25 and 26 of a somewhat curved shape, secured to each other at their upper ends as at 27. The said spring members are further secured 80 at their respective lower ends to two similarly flat members 28 and 29, of which the former is adapted to rest against the wall 13, and the latter against the cigarettes 30 positioned vertically in the casing. The construction, just described, is to the effect, that the said spring members will tend to press the cigarette designated by the reference numeral 24 against the partition 16 of the said case, from where it will be carried upward 85 by the projecting arm 23, as stated before.

90 The said front member 11 is at its bottom side arranged with an annular opening 31 adapted to fit a tube member of the box-section 15. The member 11 is further provided with 95 100

an opening 32 having hingedly connected thereto a door 33; the said opening 32 forming an air-trap for cooperation with a wick member 41 for the purpose of ignition.

5 The counter part, or back portion, of the casing comprises a rear member 14 having a somewhat curved side portion 34 adapted to snap onto and cover the side 13 of the member 11, when in closed position. The member 14 is further provided with a broad top-flange 35 constructed with a reduced portion 36 adapted to form with the opening 20 in the member 11, the outlet for the cigarette to be ejected.

10 The free end of the member 14 has hingedly connected to it a box-compartment 15, as at 37, arranged to perform a free swinging movement in order to disengage the said box-compartment with the member 14 from the front member 11.

15 The said box-compartment 15 comprises in detail a receptacle 38 adapted to contain benzine or alcohol, the said receptacle being filled through an opening at the end, closed by a tight fitting screw-member 39. From the opposite end of the said receptacle extends through a tube 40 a saturated wick 41, the latter is, when the device is not operated but in locked position, enclosed by a cap 42, preferably supported or engaged by an arm 43, 20 which in turn may be connected to the inner side of the door 33. The said compartment 15 is provided with an open space 44 and has at one side near its bottom a pivot 45 supported by a bracket 64 and adapted to engage 25 and retain a hammer 46, the latter being actuated by a spring 47 axially wound upon the said pivot; the hammer 46 consists of a forked member 52, the said forked member being connected by a ridge 48, in which is provided 30 a somewhat elliptical opening 49 adapted to 35 lift and operate a vertical spring 50 by engaging an annular enlargement 51 upon the latter. A tubular member 53 is secured to the bottom of the open section 44 of the box-compartment 15, as at 54, while it has at its 40 other end attached at one side an elongated supporting rod 55 rigidly connected to the bottom of the said receptacle 38 as at 56. The tubular member 53 has inside at its bottom 45 arranged a coiled spring 57 adapted to bring an igniter stick 58 into contact with a friction wheel 59, the latter having its periphery covered with a suitable material. The 50 said friction wheel is pivotally mounted upon the supporting rod 55 by means of a pin 60, and is actuated or forced into contact with the igniter stick 58 by means of a substantially semi-cylindrical, partly forked ratchet-member 61, the latter being in turn actuated 55 by the spring 50 during appropriate manipulation of the device. In order to secure the said ratchet member in proper position relative to the friction wheel at all times a flat leaf spring 62 is secured above the said 60 ratchet-member, the said spring having one

end rigidly attached to the side of the box-compartment as shown at 63, while its other free end is adapted to exert a constant pressure upon the said ratchet-member. For the sake of operating the said device a substantially rectangular abutment or bracket 64 supporting the pivot 45 has been formed in such a manner that it rises a trifle above the edge surface 65, thereby accomplishing through cooperation with the cam 66 formed upon the door 33 to push the latter open when the front member 11 is moved downward, or simultaneously the counter part 14 upward, during the first manipular stroke.

70 In performing the second stroke or bringing the two aforesaid members 11 and 14 together again in a closed position, a slight projection 67 formed upon the ridge 48 of the hammer catches a steep somewhat raised elevation 68 arranged upon the front member 11; the said elevation being formed with a sloping surface to the effect that the aforesaid projection 67 upon the hammer only in the closing movement catches the projection 68 and thereby sets the igniting mechanism 80 in motion by the way of the spring 50, which is strongly acted upon through the forced engagement of the hammer with the annular enlargement 51 formed upon the said spring, which in turn engages the ratchet-member 90 61 as at 69 the latter meshing with the aforesaid friction wheel 59 actuating its movement, the hammer in this instance assuming a position as indicated in Fig. 7.

95 It is obvious that the cap-member 42, attached to the door, and shielding the wick when the device is in an inoperative state, performs its opening and closing function simultaneously with the movement of the former.

100 It is further evident from the description of the device and the relative movement of its members, that a cigarette may be ejected and lighted during one complete movement or cycle. It will also be clear from the above, 105 that this device being of simple, but genuine construction, may be easily taken apart and reassembled by anyone.

110 As this constitutes a decided advantage, it deserves to be especially pointed out, that the said case may be refilled with cigarettes without being taken apart.

115 It is obvious that changes may be made in the form, construction and arrangement of the several parts, as shown, within the scope 120 of the appended claims, without departing from the spirit of the invention, and I do not therefore limit myself to the construction and arrangement shown and described herein.

125 What I claim as new, and desire to secure by Letters Patent of the United States, is:

1. A cigarette case and lighter of the class described comprising substantially a front and rear member partially provided with flanges adapted to register and snap onto each 130

- other by means of a somewhat curved form imparted to the flanges constituting the sides of the said member; a box-compartment, comprising a cigarette lighter, and being pivotally attached to the rear member of the case, an air-trap disposed in said front member and adapted for cooperation with the wick of the lighter, a trap-door having arranged a cam subject to engagement by an abutment disposed upon a bracket forming part of the ignitor box-compartment, for the purpose of regulating the movements of the said door relative to said air-trap, when the front and rear member of the case are separated during a movement in a vertical direction.
2. A cigarette case and lighter of the class described, comprising a rear member and a front member the latter being bent upon itself to form a substantially rectangular shaped open box and an end-compartment, the former adapted to receive a number of cigarettes; a plurality of springs rigidly connected and positioned in the said box in such a manner as to force the cigarettes in succession into a position suitable for ejection; a box-compartment embracing the ignition system with the cigarette lighter proper and being of a form adapted to be mounted in and cooperate with the aforesaid end-compartment of the front member, the said end-compartment being of a rectangular shape with but three sides, the said box-compartment being hingedly connected to the rear member, simultaneously serving the purpose of a connecting agent between the front and rear member, and as a slidable support during the manipulation of the two members with respect to one another.
3. A cigarette case and lighter of the class described, comprising front and rear members partly flanged, the rear member having a box-compartment embracing an ignition system hingedly attached thereto, the front member being provided with a door having a cam arranged thereupon, an air-trap for ignition purposes closed and controlled by the said door, and an opening in a vertical partition for cooperation therewith, the latter opening being adapted to register with a similar opening at the side of the box-compartment as a means of conveying air to a wick, forming part of the lighter, at a predetermined state of operation, the said function being brought about when during a move in vertical direction the abutment or bracket at the lower end of the box-compartment engages the cam of the door causing the latter to open; a cap adapted to securely enclose the said wick in order to prevent the escape of moisture, when the said device is not in operation, the said cap being carried by an arm rigidly attached to the said door, and adjusted to operate in conjunction with the movements of the latter.
4. A cigarette case and lighter of the class described, comprising two major sections, a front and a rear, detachably connected, permitting of a vertical sliding movement for the purpose of ejecting and lighting a cigarette, and permitting also through a hinged connection of a sidewise partly separating operation for the purpose of refilling the said case with cigarettes, substantially as shown and described.
5. A cigarette case and lighter of the class described, comprising two major parts detachably interengaged and adapted to cooperate vertically in a sliding manner by means of a box-compartment constituting a section of the rear major part, the said box-compartment having a substantially rectangular shape with means for ignition disposed at its front and part of the casing hingedly attached to its rear surface.
- Signed at New York city, in the county of New York and State of New York, this 17th day of March, A. D. 1928.
